AERIAL SYSTEM

William J. O'Brien and Dudley Hales Toller-Bond, London, England, assignors to The Decca Record Company, Limited, London, England, a corporation of Great Britain

Original application November 7, 1946, Serial No. 708,284. Divided and this application July 12, 1949, Serial No. 106,577

2 Claims. (Cl. 250—33)

1

This invention relates to aerial systems and has particular reference to aerial or antenna constructions which find particular utility when employed as radiators of radio frequency energy of relatively long wavelength.

This application is a division of a copending application filed by William J. O'Brien and Dudley Hales Toller-Bond, Serial No. 708,284, filed November 7, 1946, and entitled "Aerial systems."

In the radio transmitting art, great difficulty has been experienced in the past in obtaining a reasonably high radiation efficiency. This is for the reason that with antenna constructions employed prior to this invention, it was difficult, if not impossible, to obtain a relatively high radiation resistance. As is well known, the radiation efficiency is equal to the ratio of the radiation resistance to the sum of the radiation resistance, ground resistance and circuit resistance. Since the radiation resistance is proportional to the square of the effective height of the antennae in wavelengths, and since at low frequencies it is impossible to erect a mast or tower which is comparable to a quarter wavelength in height, it becomes impossible with conventional constructions to erect an antenna in which the radiation resistance bears a favourable ratio to the ground resistance. Accordingly, at best, the radiation efficiency of conventional installations is much lower than is desired.

Furthermore, since at low frequencies the height of conventional installations is low as compared with the wavelengths of the signals transmitted, the inductance and capacity of the radiator are too low for resonance and a series loading coil must be included in the circuit. This adds additional resistance to the non-radiating parts of the circuit and further reduces the radiation efficiency.

Many prior attempts have been made to improve the radiation efficiency at low frequencies and these attempts have generally taken the form of flat top antennae where a considerable length of radiator is disposed parallel to the surface of the ground. The cost of such constructions is considerably increased, due to the necessity for erecting two supporting towers instead of one. Furthermore, the two towers, not forming part of the radiating structure, absorb energy radiated from the antenna and tend to offset the gains in efficiency to be expected from the flat top construction. Also, where the radiations are to be used for navigational or direction finding purposes, further disadvantages of the flat top construction are found in the non-circular radiation

2

pattern produced, and in the horizontal polarization of the radiation which tends to increase the sky wave difficulties, particularly at night.

It is, therefore, an object of this invention to provide an antenna or radiator for use at relatively low frequencies which overcomes the above noted disadvantages by providing a higher radiation resistance and lower ground resistance than is found in simple vertical radiators of the same height.

It is also an object of this invention to provide an antenna of the character described in the preceding paragraph in which an array of radiators is so arranged that the cross-section area of the array increases away from the transmitter.

It is another object of this invention to provide an antenna of the character referred to in the preceding paragraphs which comprises a group of radiating conductors so disposed as to define a conical shape positioned with the apex thereof nearest the ground.

It is a still further object of this invention to provide an aerial system of the character hereinbefore referred to which has a large radiating surface to thereby provide an antenna having high capacity.

It is also an object of this invention to provide an antenna construction of the character hereinbefore referred to which includes a single supporting mast.

It is a still further object of this invention to provide an antenna construction of the character set forth in the preceding paragraphs which is symmetrical in horizontal cross-section to provide a circular radiation pattern.

It is another object of this invention to provide an antenna of the character hereinbefore described in which the current is fed to the radiators in such manner as to provide an effective height greatly exceeding one-half of the actual height.

Other objects and advantages of this invention will be apparent from a study of the following specifications, read in conjunction with the accompanying drawings, wherein:

The single figure is a perspective view showing the preferred embodiment of this invention.

Referring to the drawings, there is illustrated in the drawing an antenna constructed in accordance with the principles of this invention. The supporting structure for the antenna comprises a tower 50 which may be of conventional tower construction and which may be insulated from ground as by means of tower-leg insulators 51. Near the top of the tower 50 there are pro-

vided four outwardly extending horizontal booms, 52, 53, 54 and 55, the outer ends of each of the booms being supported by guys 56 connected to the extreme top of the tower 50. The outer ends of the booms are connected by horizontal conductors 57 and similarly disposed horizontal conductors 58 may be extended between adjacent ends of the booms but pulled inwardly towards the tower by means of upper radiating conductors 59 and 60 which are connected at spaced points along the length of the conductors 58 and extended to the extreme tip of the tower. The conductors 59 and 60 are also extended downwardly as indicated at 61 and 62 into connection with one of the tower legs near the base insulator 51. Similar conductors 63 may be extended from the extreme tip of each of the booms into connection with the bottom of the corresponding leg of the tower.

The antenna is preferably fed from a tuning house 64 which is placed within the area defined by the base of the tower and from which a single vertical lead 65 extends. This lead may be divided as shown in the drawing and extended into connection with each of the four legs of the tower at a point a short distance above the ground.

It will be noted that the invention described herein embodies the principle of providing an array of radiating conductors which are so disposed as to define a conical or semi-conical shape in which the apex of the cone is located nearest the ground. As will be understood, a single vertical wire antenna which is short compared to the wavelength of the signal to be radiated therefrom has neither sufficient capacity nor inductance to resonate at the frequency desired to be resonated. Such an antenna may be tuned by the addition of a series loading coil, but this reduces the radiation efficiency. Each of the antennae described herein substitutes additional capacity for the series loading inductors, the additional capacity being achieved through the use of a large number of radiating conductors so as to provide a larger surface area. Preferably to increase the surface area and to reduce the resistance due to skin effect, each of the radiating conductors is formed of multi-strand cable or similar high efficiency radio frequency conductor. Additional capacity is included by employing the supporting structure as part of the radiating array. Furthermore, by concentrating a great part of the surface area of the radiating array in that area which is located high above the ground, the effective height of the antenna is increased so as to increase the radiation resistance.

It has been found that with antennae constructed as described herein, wherein a large number of paths are provided for the flow of radio frequency current from the lead 65 to the high capacity elements of the structure, the current concentration in each of the conductors is such as to place the effective height of the antenna well above the mid-point of the actual height. Furthermore the distribution of the lines of force about the structure as a whole appears to be such as to reduce the ground resistance to a value materially lower than that associated with a simple vertical conductor of the same height. The ground resistance is further reduced by using a network of ground conductors which are buried a convenient distance below the surface of the ground and extended radially away from the base of the antenna a distance which is comparable to the height of the structure.

The effectiveness of the antenna may be seen

from the following actual operational data. A flat top antenna of conventional construction strung between masts 325 ft. high and with a relatively elaborate network of buried ground conductors, was found to have a capacity of 0.0042 mfd. When excited at 85 kc., an input power of three kilowatts produced an antenna current of 22 amperes. An antenna of the type shown in Fig. 3 having a tip height of 325 ft. and associated with a ground conductor network identical with that used in the flat top construction was found to have a capacity of 0.0040 mfd., substantially identical with the capacity of the flat top. The loading coil was therefore also substantially identical with that used on the flat top construction. When the antenna was excited at 85 kc., an input power of two kilowatts produced an antenna current of 44 amperes. Since, because of the sag in the flat top antenna, the effective heights of the two constructions were substantially equal and their radiation resistances therefore the same, it is seen that the energy radiated was increased by a factor of four with two-thirds the input power. In other words, for the same input power, the antenna was radiating six times as much energy as the flat top construction.

It should be noted that the gain in efficiency is apparently obtained principally through a reduction in ground resistance which must result from the change in character of the radiated field since both antennae were tested with identical ground conductor networks.

Thus, through an increase in the ratio of radiation resistance to ground resistance, an improvement in radiation efficiency by a factor of six or more is readily obtainable.

It should also be noted that the elimination (or the reduction in size) of the series loading coil required for a single vertical radiator materially reduces the circuit losses and also provides a lower ratio of antenna reactance to transmission resistance, thereby providing a relatively broad tuning antenna. A broadly tuned antenna will efficiently radiate a wider band of frequencies and will also produce smaller phase changes as the result of varying external conditions, an item of considerable importance when the antenna is used in radio navigation and beacon systems operating on the phase comparison principle.

From the foregoing it will be observed that this invention provides a new aerial system which is characterized by high capacity, high radiation resistance, low ground resistance, and low ratio of antenna reactance to radiation resistance. It will also be noted that the construction employed is such as to reduce to a minimum the amount of structure which must be erected, thus providing a definite advantage over the conventional flat top constructions which require a minimum of two supporting towers. It should also be noted that the structure disclosed herein is symmetrical about a vertical centre line and therefore operates to radiate a truly circular field strength pattern.

While there has been shown and described the preferred embodiment of the invention, the invention is not to be limited to any of the details shown or described herein except as defined in the appended claims.

We claim:

1. In an antenna system, the combination of: a supporting tower extending upwardly from the ground surface; means insulating said tower from ground; a plurality of outwardly extending booms secured and electrically connected to said

5

tower near the upper end thereof; tension means connecting the outer ends of each of said booms with the top of said tower; girdle conductors electrically interconnecting the outer ends of adjacent booms; and a plurality of radiating conductors extending upwardly and outwardly from the lower end of said tower, the upper ends of said conductors being spaced from each other and electrically connected to said girdle conductors, said radiating conductors being disposed outside 10 of said tower for their entire length.

2. In an antenna system, the combination of: a supporting tower extending upwardly from the ground surface, said tower tapering inwardly and upwardly from a base defined by a plurality of legs; means at each of said legs insulating said tower from ground; a plurality of outwardly extending booms secured and electrically connected 15

6

to said tower near the upper end thereof; tension means connecting the outer ends of each of said booms with the top of said tower; girdle conductors electrically interconnecting the outer ends of adjacent booms; and a group of radiating conductors for each of said legs, the conductors of each of said groups being connected at their lower ends to the associated one of said legs and extending upwardly and outwardly from the lower end of said tower, the upper ends of all of said conductors being spaced from each other and connected to said girdle conductors, said radiating conductors being disposed outside of said tower for their entire length.

WILLIAM J. O'BRIEN.
